(57) **CLAIM**

The ornamental design for a surgical bowl, as shown and described.

DESCRIPTION

FIG. 1 is a first perspective view of a surgical bowl.

FIG. 2 is a second perspective view thereof.

FIG. 3 is a top view thereof.

FIG. 4 is a bottom view thereof.

FIG. 5 is a first side view thereof; and,

FIG. 6 is a second side view thereof.

The broken lines shown in the drawings are included for the purpose of illustrating environmental elements only and form no part of the claimed design.

1 Claim, 5 Drawing Sheets

FIG. 1

FIG. 2

FIG. 3

FIG. 4

FIG. 5

FIG. 6
